CLAIM

The ornamental design for a table for double glider, as
shown and described.

DESCRIPTION

FIG. 1 is a perspective view of a table for double glider
showing my new design;

FIG. 2 is a top plan view thereof;

FIG. 3 is a right side elevation view thereof, the left side
being the same;

FIG. 4 is a front elevation view thereof, the rear being the
same; and,

FIG. 5 is a bottom plan view thereof.

The broken line showing of a double glider is for illustrative
purposes only and forms no part of the claimed design.
